UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

TUBULAR-ARM SEWING-MACHINE.

1,385,364.

Specification of Letters Patent. Patented July 26, 1921.

Application filed December 4, 1917. Serial No. 205,316.

To all whom it may concern:

Be it known that I, ALBERT H. DE VOE, a citizen of the United States, residing at Westfield, in the county of Union and State 5 of New Jersey, have invented certain new and useful Improvements in Tubular-Arm Sewing-Machines, of which the following is a specification, reference being had therein to the accompanying drawings.

- 10 This invention relates to chain-stitch sewing machines of the type known as feed-across-the-arm machines in which the work is supported on a hollow cylinder or tubular-arm joined at one end to the frame of the 15 machine and free at its other end. It is usually employed for stitching vamps in the manufacture of shoes and it is especially useful for stitching circular or endless work of various kinds.
- 20 The object of this invention is to provide a new and improved construction and arrangement for operating the feed-dog and looper in a tubular-arm machine in order to obtain a strong, durable high speed machine. A further object of this invention 25 is to improve the manner of securing the tubular-arm to the frame. And a still further object of this invention is to compact and simplify the operating mechanism which 30 must be housed within the narrow confines of the tubular-arm.

In its preferred form, the invention consists of a plurality of thread-carrying loopers operated from an inclined crank on the 35 main-shaft and located at the forward end of the tubular arm, the loopers being moved endwise transverse and sidewise in the line of feed through a carrier actuated from the inclined crank and fulcrumed on trunnion-pins whose axis intersects the axis of the main-shaft. The feed-dog is given four motions 40 to advance the work across the arm through a pair of telescoping feed rock-shafts each actuated by an eccentric on the main-shaft and the length of stitch is varied through 45 an adjustable connection accessible from the end of the tubular arm.

In its preferred form the invention is illustrated in the accompanying drawings in 50 which Figure 1 is a perspective view of the

operating mechanism housed within the tubular arm which is indicated partly in dotted lines and partly in section for the sake of clearness, the looper and looper-carrier being omitted also for the sake of clearness. 55 Fig. 2 is a perspective view of the main-shaft and loopers operated thereby. Fig. 3 is a longitudinal section of the free end of the arm taken on the line A—B Fig. 4. Fig. 4 is an end view of the free end of the 60 tubular arm with the end cap omitted. Fig. 5 is an end view of the tubular arm, presser-foot and needles with the end cap in position. Fig. 6 is a perspective view looking at the inside of the end cap. Figs. 7 and 8 65 show in perspective the members of a linkage connecting the feed rock-shaft with the feed-dog carrier. Fig. 9 is a perspective of the feed rock-shaft and parts carried thereby. Fig. 10 is a perspective view of the feed-lift rock-shaft. Fig. 11 shows the feed-dog carrier. Fig. 12 illustrates one of the sector plates carrying the bearings for the trunnion-pins of the looper-carrier. Fig. 13 shows a modified arm. 75

Rising from the feet or legs 1 is the vertical standard 2 having a boss 3 apertured horizontally as indicated at 4 to receive the tubular or hollow arm 5 for supporting the work. Any suitable means may be employed 80 to secure the arm 5 within the boss 3, the set-screws 6 shown being simple and inexpensive means for that purpose. The boss 3 is preferably made long enough to get a good grip on the portion of the arm inserted 85 into it. The arm being lengthwise as well as circumferentially adjustable in the boss may be readily located with the needle-holes in the throat-plate 7 in register with the needles 8. 90

The needles 8 in a clamp 9 on the needle-bar 10 reciprocate through needle-holes in the usual pivoted presser-foot 11 on the presser-bar 12 supported in the head of an overhanging arm (not shown) and operated 95 in any suitable manner.

In its preferred form the machine is of the two-needle two-looper type for making a double thread chain-stitch but it is to be understood that the invention is not limited 100

to the specific type of stitch-forming mechanism mentioned inasmuch as in certain respects the invention embraces other forms of mechanism. A single-needle and looper 5 for instance could be used as well as two or more of each and in some instances it might be found desirable to substitute a non-thread carrying looper instead of a thread-carrying looper.

10 The two thread-carrying loopers 13 shown in Fig. 2 are each secured by screws 14 to a carrier 15 having trunnion-pins 16 extending from opposite sides thereof into bearings 17 integral or in any other suitable manner fixed to the sector-shaped plates 18, see Fig. 12, which are removably secured by screws 19 to the arm on opposite sides thereof and whose outer curved surfaces define portions of the external surface of the arm. The 15 trunnion-pins 16 are in a line and at substantially right angles to the blades of the loopers 13. On the trunnion-pins 16 and within the bearings the loopers 13 may oscillate in planes parallel to the axis of the arm and 20 may move bodily sidewise in a direction at right angles to the planes of their endwise movements.

15 A socket 20 in the looper-carrier embraces a pin 21 carried by a sleeve 22 split in half and clamped together by the screws 23 so as to loosely and slidably embrace an inclined crank-pin 24 on the main-shaft 25 of the machine which is located in the lower portion and centrally of the arm directly 25 beneath its longitudinal axis. The relation of the axes of the main-shaft of the inclined crank and of the trunnion-pins is important. The axis of the main-shaft 25 intersects the axis of the inclined crank 24 and 30 slightly to one side of the point of intersection the axis of the trunnion-pins 16 intersects the axis of the main-shaft 25. By reason of this relative arrangement the rocking of the pin 21 socketed in the carrier 15 35 not only imparts endwise movements to the loopers about the trunnion-pins as a fulcrum, but also imparts bodily sidewise movement thereto so that the loopers may enter the needle-loop on one side and retreat on 40 the other side of the needle. From this description it will be seen that the looper is supported and actuated above and on the same side of the main-shaft of the machine. It will also be seen that the endwise and 45 sidewise movements of the looper are positive and without lost-motion which is desirable and necessary to attain high speed in the operation of the machine.

50 Directly above the loopers 13 and the inclined crank 24 on the main-shaft is located the feed-dog 26, the serrated teeth of which are arranged to conform with the curvature of the arm. The shank 27 of the feed-dog is secured in a familiar manner between the 55 ribs 28, Fig. 11, on a U-shaped feed-dog

carrier 29. Projecting laterally from the opposite ends of the U-shaped feed-dog carrier 29 are pins 30 pivotally supported in bearings 31 at the free ends of crank-arms 32—33 one fixed and the other adjustably 70 clamped to a tubular shaft 34 which is rocked from an eccentric 35 on the main-shaft 25 through a pin-and-socket connection 36 best shown in Fig. 1. By these means vertical components of motion are 75 imparted to the feed-dog across the arm.

80 Horizontal components of motion are imparted to the feed-dog from an eccentric 37 (Fig. 2 only) on the main-shaft adjacent the lift eccentric 35 and separated therefrom by a spacing collar 38. The strap end 39 of a short pitman 40 embraces the feed-eccentric 37 and at its opposite end is pinned as at 41 to a crank-arm 42 fastened in any suitable manner on a comparatively light 85 feed rock-shaft 43 which extends through the tubular shaft 34 to the free end of the arm 5 where it is equipped with a second crank-arm 44 having a curved T-shaped slot 45 receiving a block 46 in which is tapped 90 a screw 47 whose cylindrical head is nicely machined so that it may function as a crank-pin. A washer 48 is interposed between the head of the screw 47 and the outer walls of the slot 45 so as to permit clamping of the block any desired distance in the curved T-slot 45 from the axis of the feed rock-shaft 43. Embracing the head of the screw 47 is one end of a link 49, Fig. 8, whose other end carries a pin 50 extending 100 into an apertured boss 51, Fig. 7, on a triangular shaped plate 52 having a bushing 53 receiving the extreme end of the main-shaft 25 beyond the inclined crank 24, the plate 52 being connected by a second link 105 54 to a curved and depending extension 55 of the feed-dog carrier 29. Through the two links 49—54 and the triangular shaped plate 52, which is really a lever having a fixed fulcrum in the end cap 56 coaxial with 110 the main-shaft, rocking movements of the feed rock-shaft impart horizontal components of motion to the feed-dog which components may be varied in length.

115 The end-cap 56 of the machine is of the peculiar shape shown in perspective in Fig. 6 and in section Fig. 3. It is cut away inside and at the lower rear portion to accommodate the slotted crank 44 and link 49 for imparting feeding movements to the dog, the link 49 which is removable being steadied against accidental displacement by the overlying wall 57 of the end-cap 56. This end-cap affords a bearing 58 for the bushing 53 and the main-shaft 25 which is 120 indicated clearly in Fig. 3. The end-cap is accurately positioned upon the arm by the three clamp-screws 59 and by setting of a nose 60 against a ledge 61 in a forwardly projecting and integral portion 62, Fig. 1, 125 63.

of the arm. This bearing 58 for the main-shaft in the end-cap materially assists in confining the movements of the loopers to a fixed path and preventing vibration and 5 overthrow thereof out of a fixed path.

A needle-guard 63 of old and well known form is carried by the end-cap. Hinged at 64 to the rear of the end-cap 56 is a cover-plate 65 adapted to be held closed by the 10 spring 66 engaging a hook 67 carried by the cover-plate and thus access is had to the loopers for threading them up. Through the end-cap a U-shaped opening is cut as indicated at 68 to permit the insertion of 15 a screw-driver for adjusting the position of the screw-pin 47 on the crank-arm 44 of the feed rock-shaft 43 and thus regulating the feed to vary the length of stitch.

In addition to the bearing 58 in the end- 20 cap which receives the bushing 53 of the triangular plate 52 which in turn receives the extreme end of the main-shaft, the main-shaft is supported by a bearing 69 intermediate the length of the tubular-arm and again 25 by a bearing 70 adjacent the junction of the tubular-arm and the vertical standard of the frame. These three bearings are the only bearings for the main-shaft of the machine which shaft extends beyond the end 30 of the tubular-arm into the vertical standard 2 where it is provided with a crank 71 embraced by the strap end of a pitman 72 suitably connected to the needle-bar operating shaft (not shown). The main-shaft extends 35 on through the end-wall of the vertical standard 2 where it carries a belt-wheel 73 through which power is supplied for running the machine.

The telescoping rock-shafts 34-43 are 40 journaled in a long bearing 74 extending through and on opposite sides of the vertical plane of the feed-motion and a relatively short bearing 75 immediately in rear of the central bearing 69 for the main-shaft. 45 The feed rock-shaft 43 is provided with an additional bearing 76 beyond its crank-arm 42 which is operated by the pitman embracing the feed-eccentric 37 on the main-shaft. It will be noticed that if a cross-section is 50 taken through the junction of the tubular arm and frame that only a single shaft, the main shaft 25, will be cut.

By telescoping the feed rock-shafts and by actuating them from the feed eccentrics 55 on the main-shaft located intermediate the ends of the arm the mechanism has been compacted within the cramped space available in the arm without sacrificing mechanical efficiency of operation. Furthermore, the 60 short length of the telescoping rock-shafts prevents any appreciable or prohibitive amount of torsion.

The thread is passed from the loopers 13 through the wire eyelet 77, Fig. 1, secured 65 internally of the arm and passing through

an inclined hole 78 near the junction of the arm with the frame out to a take-up 79 constructed and operated substantially in the manner fully described in my copending application Serial No. 114,503, filed August 70 12, 1916, but specifically forming no part of the present invention.

Preferably the inclined crank 24 is formed on a small light shaft proportioned to carry the load imposed upon it in actuating the 75 loopers. This light shaft is socketed in a larger portion of the main-shaft 25 as indicated at 80, Fig. 2, and set screwed in place as shown at 81. Obviously, however, the main-shaft may be made integral or otherwise if desired.

The manner of securing the tubular arm 5 to the vertical standard 2 of the frame is novel and advantageous. The arm alone carries the main-shaft and all the mechanism 85 operated therefrom for actuating the feed-dog and loopers. The mechanism is nicely compacted within the arm. In the manufacture of the machine the tubular arm may thus be made complete in itself. In assembling the arm and frame together the former is inserted in the opening 4 of the boss 3 and the arm is readily positioned with the needle-holes in the throat-plate in line with the needle-paths by turning it about its own 90 axis and by adjusting it lengthwise. After positioning the tubular arm in this manner tightening of screw 6 will hold the tubular arm in proper position. No nice dimensioning of parts within the tubular arm to link 95 up with other members within the frame is necessary. The end of the pitman 72 being split may be readily strapped about the crank 71 on the main shaft. By this simple manner of joining the arm to the frame the manufacture and assemblage of the parts within the tubular arm may be made expeditiously and accurately without the necessity of precise measurement of any parts in the arm to link 100 or connect up with a number of other parts 110 in the frame, crank 71 and pitman 72 being the only driving connection between the mechanisms in the frame and arm.

In the feeding mechanism the sustaining 115 of the feed dog carries on the opposite sides of the plane in which the feed-dog moves affords a rigid support insuring against yielding of the feed-dog under the strain of advancing the work and making its action certain and positive. 120 The nesting of the feed rock-shafts economizes space. Regulation of the feed being seldom necessary the simple adjustment accessible through the end cap for regulating the stitch length meets the demand and answers the purpose without expensive additional parts in the form of levers, etc., heretofore employed.

In the looper-operating mechanism compactness of the organization without sacri- 130

fice of mechanical efficiency is also a feature. While the loopers shown and described have a bodily sidewise movement as well as an endwise movement, a single looper with an 5 endwise movement only may be employed, if desired, by simply locating the bearings 17 for the trunnion-pins 16, so that the axis of the bearings will intersect the axis of the main-shaft at the same point as the axis of 10 the inclined crank.

Attention is called to the fact that the adjustment of the block 46 in the curved T-shaped slot 45 to vary the length of feed effects variations at the rear end only of the 15 feed-dog's stroke. In other words the feed-dog always rises and engages the work at the same point relative to the needles but it drops away and disengages itself from the work sooner or later depending on whether 20 the stitch be short or long. This confining of the variation in the length of feed to the rear end of the feed-dog stroke is due to the fact that the center of curvature of the T-shaped slot 45 is coincident with the axis of 25 pin 50 carried by the link 49 when the feed-dog rises into engagement with the work. In other words the slotted crank-arm 44 arrives at neutral position relative to the link 49 when the feed is about to commence.

30 While the previously described form of tubular arm is preferred I contemplate the use of a modified form of arm shown in Fig. 13 which is similar in all respects to the preferred form with the exception that an 35 extension 5' thereof passes through the two opposed vertical walls of the standard 2 instead of passing through the boss 3 only in one wall of said standard. An additional bearing 82 is carried by the extension 5' and 40 the extension is cut away as indicated at 83 and 84 to furnish clearance for the crank 71 and the pitman 72. In this modified form of arm the advantages of sustaining all bearings for the main-shaft on the tubular arm 45 alone are preserved where the load on the main-shaft is too great to permit of locating the belt-wheel 73 as far away from the nearest bearing as is shown in Fig. 1. The advantages of having all the bearings for the 50 main-shaft on the tubular arm may be partly realized by locating a bearing for the main-shaft in the end wall of the vertical standard adjacent the belt-wheel and it is to be distinctly understood that such an arrangement 55 is regarded within the scope of the invention in some of its aspects as defined by some of the claims.

It will be noticed by glancing at Figs. 2 and 5 that the supports (bearings 17) for the 60 looper carrier are front and back of the line of needle actuation and that the supports (bearings 58 and 69) for the inclined actuating crank 24 are on opposite sides of the line of needle-actuation. It will thus be seen 65 that there are two pairs of supports and if

the members of each pair are connected by a straight line that the lines will cross each other at about right angles. Hence it will be seen that the looper carrier and its actuating inclined crank are each provided with 70 bearings or supports on opposite sides of the line of needle-actuation.

Having thus set forth the nature of the invention, what I claim herein is:—

1. In a sewing machine, a frame having a 75 tubular work-arm around which is a clear space facilitating manipulation of the work, a single rotating shaft only extending through the junction of the arm and frame, a feed-dog, a looper, means for imparting 80 four motions to said feed-dog and endwise movements to said looper from said rotating shaft, said means being located entirely within the tubular arm.

2. In a sewing machine, a frame having a 85 tubular work-arm around which is a clear space facilitating manipulation of the work, a single rotating shaft only extending through the junction of the arm and frame, a feed-dog, a looper, means for imparting 90 four motions to said feed-dog and endwise and sidewise movements to said looper from said rotating shaft, said means being located entirely within the tubular arm.

3. In a sewing machine having stitch-forming mechanism including a needle, a frame having a tubular work-arm, a single driving shaft only extending through the junction of the arm and frame, a feed-dog, 95 a looper, means for actuating said feed-dog to advance the work and said looper to operate with the needle in the formation of stitches, said means being located entirely within the tubular arm and including a rock-shaft disposed parallel to the driving shaft and of a length less than the length of said arm, said rock-shaft imparting to said feed-dog movement in one direction, and means 100 for imparting to said feed-dog movement in a direction at right angles to the first 105 mentioned direction.

4. In a sewing machine having stitch-forming mechanism including a needle, a frame having a tubular work-arm, a single driving shaft only extending through the junction of the arm and frame, a feed-dog, 110 a looper, means for actuating said feed-dog to advance the work and said looper to operate with the needle in the formation of stitches, said means being located entirely 115 within the tubular arm and including a pair of rock-shafts disposed parallel to the driving shaft and of a length less than the length of said arm, said rock-shafts imparting to said feed-dog movements in a plane at right 120 angles to each other.

5. In a sewing machine having stitch-forming mechanism including a needle, a frame having a tubular work-arm, a single driving shaft only extending through the 125

- junction of the arm and frame, a feed-dog, a looper, means for actuating said feed dog to advance the work and for imparting endwise and sidewise movements to said looper, 5 said means being located entirely within the tubular arm and including a rock-shaft disposed parallel to the driving shaft and of a length less than the length of said arm for imparting to said feed-dog movements in one direction, and means for imparting to said feed dog movement in a direction at right angles to said first mentioned direction.
6. In a sewing machine having stitch-forming mechanism including a needle, a frame having a tubular work-arm, a single driving shaft only extending through the junction of the arm and frame, a feed-dog, a looper, means for actuating said feed-dog to advance the work and for imparting endwise and sidewise movements to said looper, 10 said means being located entirely within the tubular arm and including a pair of rock-shafts as disposed parallel to the driving shaft and of a length less than the length of said arm for imparting to said feed-dog movements in directions at right angles to each other.
7. In a sewing machine, a frame having a tubular work-arm, a single rotating shaft only extending through the junction of the arm and frame, a feed-dog arranged to operate in a plane transverse the length of the tubular work-arm, a looper, means for actuating said feed dog to advance the work 15 and for imparting endwise movements to said looper, said means being located entirely within the tubular arm.
8. In a sewing machine, a frame having a tubular work-arm, a single rotating shaft only extending through the junction of the arm and frame, a feed-dog arranged to operate in a plane transverse the length of the tubular work-arm, a looper, means for actuating said feed-dog to advance the work 20 and for imparting endwise and sidewise movements to said looper, said means being located entirely within the tubular arm.
9. In a sewing machine having stitch-forming mechanism including a needle, a frame having a tubular work-arm, a rotating shaft extending through the junction of the arm and frame, a feed-dog arranged to operate in a plane transverse the length of said tubular arm, a looper, means for actuating said feed-dog to advance the work 25 and said looper to cooperate with the needle in the formation of stitches, said means comprising a plurality of eccentric elements on said rotating shaft within the tubular arm 30 and operating connections therefrom to the feed-dog and looper.
10. In a sewing machine having stitch-forming mechanism including a needle, a frame having a tubular work-arm, a rotating shaft extending through the junction of 35
- the arm and frame, a feed-dog arranged to operate in a plane transverse the length of said tubular arm, a looper, means for actuating said feed-dog to advance the work and said looper to coöperate with the needle in 70 the formation of stitches, said means comprising a plurality of eccentric elements on said rotating shaft within the tubular arm and operating connections therefrom to the feed-dog and looper, said connections including a pin-and-socket device.
11. In a sewing machine having stitch-forming mechanism including a needle, a frame having a vertical standard provided with a horizontally extending aperture, a tubular work-arm shaped in cross-section to fit said aperture within which it is secured, a feed-dog and a looper operatively supported within said tubular arm adjacent its free end, means for imparting work-advancing 80 movements to said feed-dog and stitch-forming movements to said looper.
12. In a sewing machine having stitch-forming mechanism including a needle, a frame having a vertical standard provided with a horizontally arranged opening, a tubular work-arm shaped at one end to fit within said opening, and having a throat-plate provided with a needle-hole, clamping means for securing said arm within the opening in said vertical standard with the needle-hole in line with the needle, work-feeding and needle-coöperating devices movably supported within said tubular arm, and means for operating said devices.
13. In a sewing machine having stitch-forming mechanism including a needle, a frame having a vertical standard provided with a boss having a horizontally arranged opening, a tubular work-arm shaped to fit within said boss and free to be adjusted lengthwise, clamping means for holding said arm in said boss and permitting adjustment of the arm lengthwise in said opening as well as about its own longitudinal 95 axis, a feed-dog, a looper, means for imparting movements to said feed-dog and looper to cooperate with the needle in the formation of stitches.
14. In a sewing machine having stitch-forming mechanism including a needle, a frame having a tubular work-arm, a main-shaft arranged within the work-arm, a feed-dog operatively supported adjacent the free end of said tubular arm, means for actuating 105 said feed-dog in a plane transverse the tubular arm and from said main-shaft, said means being located entirely within the tubular work-arm, a looper, a looper-carrier mounted for oscillatory movement about a fixed axis directly beneath the feed-dog, and means for actuating said looper-carrier to cause the looper to enter and shed the loops thrown out by the needle.
15. In a sewing machine having stitch- 110
- 120
- 125
- 130

forming mechanism including a needle, a frame having a tubular work-arm, a main-shaft arranged within the work-arm, a feed-dog operatively supported adjacent the free 5 end of said tubular arm, means for actuating said feed-dog in a vertical plane transverse said tubular arm, and from said main-shaft, said means being located entirely within the tubular work-arm, a main driving shaft, a 10 looper, a looper-carrier mounted for oscillatory movement about a fixed axis directly beneath the feed-dog, and connections between said main driving shaft and the looper-carrier for imparting endwise movements to the looper.

16. In a sewing machine having stitch-forming mechanism including a needle, a frame having a tubular work-arm, a main-shaft arranged within the work-arm, a feed-dog operatively supported adjacent the free 20 end of said tubular arm, means for actuating said feed-dog in a plane transverse said tubular arm, and from said main-shaft, said means being located entirely within the tubular work-arm, a looper, a looper-carrier mounted for oscillatory movement upon and for bodily movement along a fixed axis directly beneath the feed-dog, and means for actuating said looper-carrier to cause the 25 looper to enter and shed the loops thrown out by the needle.

17. In a sewing machine having stitch-forming mechanism including a needle, a frame having a tubular work-arm, a feed-dog operatively supported adjacent the free 35 end of said tubular arm, means for actuating said feed-dog in a plane transverse said tubular arm, a main driving shaft, a looper, a looper-carrier mounted for oscillatory 40 movement about a fixed axis directly beneath the feed-dog, and connections between said main driving shaft and the looper-carrier for imparting endwise movements to the looper, said connections including an inclined 45 crank on the main-shaft intermediate its ends, and bearings for said main-shaft on opposite sides of the inclined shaft.

18. In a sewing machine having stitch-forming mechanism including a needle, a frame having a tubular work-arm, a feed-dog operatively supported adjacent the free 50 end of said tubular arm, means for actuating said feed-dog in a vertical plane transverse the axis of said tubular arm, a main driving shaft having an inclined crank intermediate its ends, bearings for said main-shaft on opposite sides of the inclined crank, a looper, a looper-carrier mounted for oscillatory movement about a fixed axis directly 55 beneath the feed-dog, and means for actuating said looper-carrier to cause the looper to enter and shed the loops thrown out by the needle.

19. In a sewing machine having stitch-forming mechanism including a needle, a 60

frame having a tubular work-arm, a feed-dog, a looper, and means for imparting operative movements to said feed-dog and looper including a rotary main-shaft extending the entire length of the arm and beyond the arm 70 into the frame, and extensive bearing surface for said main-shaft carried solely by the tubular arm.

20. In a sewing machine having stitch-forming mechanism including a needle, a frame having a tubular work-arm, a feed-dog, a looper, and means for imparting operative movements to said feed-dog and looper including a main-shaft extending the entire length of the arm and beyond the arm 75 into the frame, a plurality of bearings for said main-shaft carried solely by the tubular arm, and means sustaining the tubular arm in the frame permitting lengthwise adjustment of the arm.

21. In a sewing machine having stitch-forming mechanism including a needle, a frame having a tubular work-arm, a feed-dog, a looper, a rotary main-shaft, means for imparting movements to said feed-dog and looper from the main-shaft, and bearings for said main-shaft supporting it on 90 opposite sides of a vertical plane containing the line of seam formation.

22. In a sewing machine having stitch-forming mechanism including a needle, a frame having a tubular work-arm, a feed-dog and a looper operatively supported within said tubular arm adjacent its free end, a main driving shaft, a rock-shaft disposed parallel to said main driving shaft, connections between said feed-dog and rock-shaft for imparting vertical components of motion to the feed-dog, bearings for supporting said rock-shaft on opposite sides of the vertical plane of feed, and means for imparting horizontal components of motion to the feed-dog.

23. In a sewing machine having stitch-forming mechanism including a needle, a frame having a tubular work-arm, a feed-dog and a looper operatively supported within said tubular arm adjacent its free end, a main driving shaft, a rock-shaft disposed parallel to said main driving shaft, connections between said feed-dog and rock-shaft for imparting horizontal components of motion to the feed-dog, bearings for supporting said rock-shaft on opposite sides of the plane in which the feed-dog moves, and means for imparting vertical components of motion to the feed-dog.

24. In the tubular work-arm of a sewing machine having stitch-forming mechanism including a needle, a looper, means for operating said looper, a main driving shaft extending within the tubular arm, said looper operating means being actuated solely from the main-shaft and being housed entirely within the tubular work-arm,

feed-dog, and means for imparting four motions to said feed-dog from said main driving shaft including a pair of parallel rock-shafts.

5 25. In the tubular work-arm of a sewing machine having stitch-forming mechanism including a needle, a looper, means for operating said looper, a main driving shaft, a feed-dog, and means for imparting four 10 motions to said feed-dog from said main driving shaft including a pair of telescoping rock-shafts.

15 26. In the tubular work-arm of a sewing machine having stitch-forming mechanism including a needle, a looper, and means for operating said looper, a main driving shaft, a feed-dog, means for imparting four motions to said feed-dog from said main driving shaft including a pair of telescoping 20 rock-shafts, and bearings for said telescoping rock-shafts on opposite sides of the vertical plane of feed.

25 27. In the tubular work-arm of a sewing machine having stitch-forming mechanism including a needle, a feed-dog, a looper, a main driving shaft, means for actuating said feed-dogs from said main driving shaft including a pair of telescoping rock-shafts, bearings for said rock-shafts on opposite 30 sides of the vertical plane of feed, and connections between said main driving shaft and said looper for imparting endwise and sidewise movements thereto, said main driving shaft having bearings on opposite sides 35 of the vertical plane of feed.

28. In the tubular work-arm of a sewing machine having stitch-forming mechanism including a needle, a main driving shaft located in the lower part of the arm, a looper, 40 a looper-carrier mounted for oscillatory movement upon and for bodily movement along a fixed axis, an inclined crank element on said main driving shaft, connections between the crank element and looper-carrier for imparting endwise and sidewise 45 movements to the looper, and supports for both the looper-carrier and its actuating inclined crank on opposite sides of the line of needle actuation.

50 29. In the tubular work-arm of a sewing machine having stitch-forming mechanism including a needle, a looper, means for operating the looper, a feed-dog mounted to function in a plane transverse the length

55 of the arm, a feed-dog carrier, eccentric elements on the main-shaft within the arm, a pair of rock-shafts actuated each by one of said eccentrics, arms on one of said rock-shafts at opposite sides of the vertical plane 60 of feed motion for supporting and lifting said carrier to impart lifting movements to said feed-dog, an arm on the other of said rock-shafts, and connections from the last-named arm to the feed-dog carrier for imparting feeding movements to the dog, said

connections being located between the vertical plane of feed motion and the tip end of the arm.

30. In the tubular work-arm of a sewing machine having stitch-forming mechanism including a needle, a main driving shaft located in the lower portion of said arm, a looper, means for actuating said looper from said main driving shaft, a feed-dog arranged to operate across the arm, a feed-dog carrier 70 having a curved extension depending to a point adjacent the lower side of said arm, a pair of rock-shafts actuated independently from said main-shaft, arms on one of said rock-shafts at opposite sides of the vertical plane of feed motion and pivotally supporting said carrier whereby the feed-dog is given its vertical components of motion, an arm on the other of said rock-shafts, and connections from the last-named arm to the 75 feed-dog carrier for imparting horizontal components of motion to the dog, said connections including a lever having a fixed fulcrum below and immediately adjacent one of the pivotal supports for the carrier 80 whereby the work-advancing movements to the feed-dog conform to the external curvature of the arm.

31. In the tubular work-arm of a sewing machine having stitch-forming mechanism 95 including a needle, a main driving shaft located in the lower portion of said arm, a looper, means for actuating said looper from said main driving shaft, a feed-dog arranged to operate across the arm, a feed-dog carrier having a curved extension depending to a point adjacent the lower side of said arm, a pair of rock-shafts actuated independently from said main-shaft, arms on one of said rock-shafts at opposite sides of the vertical plane of feed motion and pivotally supporting 100 at their free ends said carrier whereby the feed-dog is given its vertical components of motion, an arm on the other of said rock-shafts, and connections from the last-named 105 arm to the feed-dog carrier for imparting horizontal components of motion to the dog, said connections including a lever having a fixed fulcrum coaxial with the main-shaft below and immediately adjacent one of the 110 pivotal supports for the carrier whereby the work-advancing movements to the feed-dog conform to the external curvature of the arm.

32. In the tubular work-arm of a sewing 120 machine having stitch-forming mechanism including a needle, a main driving shaft located in the lower portion of said arm, a looper, means for actuating said looper from said main driving shaft, a feed-dog arranged to operate across the arm, a feed-dog carrier having a curved extension depending to a point adjacent the lower side of said arm, a pair of telescoping rock-shafts actuated 125 independently from said main-shaft, 130

arms on one of said rock-shafts at opposite sides of the vertical plane of feed motion and pivotally supporting at their free ends said carrier whereby the feed-dog is given its vertical components of motion, an arm on the other of said rock-shafts, and connections from the last-named arm to the feed-dog carrier for imparting horizontal components of motion to the dog, said connections including a lever having a fixed fulcrum below and immediately adjacent one of the pivotal supports for the carrier whereby the work-advancing movements to the feed-dog conform to the external curvature of the arm.

33. In the tubular work-arm of a sewing machine having stitch-forming mechanism including a needle, a main driving shaft located in the lower portion of said arm, a looper, means for actuating said looper from said main driving shaft, a feed-dog arranged to operate across the arm, a feed-dog carrier having a curved extension depending to a point adjacent the lower side of said arm, a pair of telescoping rock-shafts actuated independently from said main-shaft, arms on one of said rock-shafts at opposite sides of the vertical plane of feed motion and pivotally supporting said carrier whereby the feed-dog is given its vertical components of motion, an arm on the other of said rock-shafts, and connections from the last-named arm to the feed-dog carrier for imparting horizontal components of motion to the dog, said connections including a lever having a fixed fulcrum coaxial with the main-shaft below and immediately adjacent one of the pivotal supports for the carrier whereby the work-advancing movements to the feed-dog conform to the external curvature of the arm.

34. In the tubular work-arm of a sewing machine having stitch-forming mechanism including a needle, an end cap closing the free end of said tubular arm, a main driving shaft, a looper, means for operating the looper from the main driving shaft, a feed-dog, means for imparting work-advancing movements to said feed-dog including an adjustable connection for varying the length of feed accessible through said end cap without removal of the same from the arm.

35. In a chain-stitch sewing machine having stitch-forming mechanism including a needle, a frame having a tubular work-arm, and housed within said arm a looper, means for operating said looper, a main driving shaft, a feed-dog, and means for imparting four motions to said feed-dog from said main driving shaft, said means including an adjustment for varying the feed, and the variations in the feed occurring at the rear end only of the feed stroke.

36. In the tubular work-arm of a sewing machine having stitch-forming mechanism including a needle, an end cap closing the free end of said tubular arm, a main driving shaft, a looper, means for operating the looper from the main driving shaft, a feed-dog, means for imparting work-advancing movements to said feed-dog including an adjustable connection for varying the length of feed located between the free end of said tubular work-arm and the vertical plane in which the feed-dog moves.

37. In a sewing machine having a tubular work-arm, stitch-forming mechanism including a needle, a rotary main-shaft within the tubular work-arm, an inclined crank on said rotary main-shaft intermediate its ends, a looper, a looper-carrier mounted for oscillatory movement about a fixed axis, means for imparting oscillatory and bodily sidewise movements to said looper-carrier including a sleeve provided with a cylindrical aperture adapted to embrace the inclined crank, and a pin-and-socket connection between the sleeve and the looper-carrier.

38. In a sewing machine having stitch-forming mechanisms including a coöperating needle and looper, a frame having a vertical standard, a hollow work-arm externally cylindrical at one end, said vertical standard being provided with a cylindrical bore whose axis is substantially perpendicular to that of the vertical standard, and means for adjustably securing said externally cylindrical end of said work-arm in the bore provided in the vertical standard.

39. In a sewing machine having stitch-forming mechanism including a needle, a frame having a standard, a tubular work-arm, a shaft within said work-arm, work-feeding and looper mechanisms in said work-arm, operative connections from the shaft to the work-feeding mechanism and to the looper mechanism for imparting endwise and sidewise movements to the looper, said connections being supported wholly by the work-arm and means for removably securing the work-arm to the standard.

40. In a sewing machine having stitch-forming mechanism including a needle, a loop-taker, means for operating said loop-taker, a main-shaft, a feed-dog, means for imparting four motions to said feed-dog including a pair of telescoping shafts, driving connections from the main shaft to one of said telescoping shafts for imparting rising and falling movements to the feed-dog and to the other shaft for imparting feeding movements to the feed-dog.

In testimony whereof I have signed my name to this specification.

ALBERT H. DE VOE.
